(57) **CLAIM**

The ornamental design for a toothbrush replacement head, as shown and described.

DESCRIPTION

FIG. 1 is a front, right, and top perspective view of a toothbrush replacement head showing my new design; FIG. 2 is a rear, left, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is an enlarged top plan view thereof; FIG. 8 is an enlarged bottom plan view thereof; FIG. 9 is an enlarged view of portion 9 shown in FIG. 1; FIG. 10 is an enlarged view of portion 10 shown in FIG. 3; FIG. 11 is an enlarged view of portion 11 shown in FIG. 5; and, FIG. 12 is an enlarged view of portion 12 shown in FIG. 6. The dash-dash broken lines in the drawings depict portions of the toothbrush replacement head that form no part of the claimed design. The dot-dash broken lines represent boundaries of the enlarged portion that form no part of the claimed design.

1 Claim, 12 Drawing Sheets
